UNITED STATES PATENT OFFICE.

NATHAN G. PERRY AND CHARLES E. HULTING, OF DOUGLAS, ARIZONA, ASSIGNEES OF ONE-THIRD TO CHARLES X. THOMPSON, OF DOUGLAS, ARIZONA.

BASE-SUPPORT.

1,321,666.

Specification of Letters Patent.

Patented Nov. 11, 1919.

Application filed March 9, 1918. Serial No. 221,456.

To all whom it may concern:

Be it known that we, NATHAN G. PERRY and CHARLES E. HULTING, citizens of the United States of America, residing at Douglas, in the county of Cochise and State of Arizona, have invented certain new and useful Improvements in Base-Supports, of which the following is a specification.

This invention relates to base supports and is adapted to be placed on the running board of an automobile to form a suitable retaining support for different objects and is particularly adapted to be used as a suitable support for a temperature retaining canteen as set forth in our pending application Serial No. 207,914, filed December 19, 1917, the object being to provide this support with suitable cushioning means to relieve the canteen of as much jar as possible.

20 In the accompanying drawings:—

Figure 1 is a perspective view of our device,

Fig. 2 is a top plan view of the device, and,

Fig. 3 is a transverse vertical section on line 3—3 of Fig. 2.

The support consists preferably of end members 1 and 2 and front and back members 3 and 4, which are preferably constructed of a single piece of angle-iron of sufficient length to be bent into the desired shape. The base portion of the angle-iron in its developed length is adapted to be notched as at 5, thereby forming a miter when the angle-iron is bent up in the desired shape.

35 Triangular pieces 6, cut in the proper shape are soldered or sweated on at the corners over the mitered edges in order to properly stiffen the frame at this point. 7, 40 indicates a plurality of triangular rubber or leather blocks or other suitable material which are adapted to be placed in the corners of the frame as illustrated to form a

cushioning means for the canteen 8, shown in dotted lines in Fig. 1.

45 The rear side member 4, is provided with an opening 9, and the front member 3, is provided with a notch 10, open on one side as illustrated.

This opening and slot 9 and 10, are adapted to receive projections 11 and 12 arranged on the front and rear sides of the canteen which are adapted to be received within the opening 9, and the slot 10, the member 11, being held within the slot 10 by a suitable latch 12', pivoted as at 13, to the front edge 3, of the frame and of sufficient length to bridge over the projection 11, of the canteen and pass under the lug 14 struck up from the front portion 3, thereby securely holding 60 the canteen within the rectangular frame.

Headed bolts 15—15 are adapted to pass through the base portion of the triangular pieces 6 and be received in suitable openings in the running board of the automobile in order to securely fasten the device in position.

65 It is obvious that we have devised a very simple and efficient supporting frame and one from which the canteen is readily attached to or detached from and one wherein the most of the jar is taken up in the frame, thereby relieving the canteen of as much strain or undue shaking as possible.

We claim:

A base support consisting of a rectangular frame having triangular corner pieces to make it rigid and provided at opposite points with closed and open slots adapted to receive projections on a canteen and a suitable latch pivoted to the frame in position to engage and secure the projection in the open slot.

75 80 85 In testimony whereof we affix our signatures.

NATHAN G. PERRY.
CHARLES E. HULTING.
